United States Patent Office

Des. 216,701
Patented Mar. 3, 1970

216,701

DATA PROCESSING CONSOLE UNIT

James Jordan, Townsend, Mass., assignor to Digital Equipment Corporation, Maynard, Mass.

Filed Dec. 23, 1968, Ser. No. 15,091

Term of patent 14 years

Int. Cl. D14—02

U.S. Cl. D26—5

FIG. 1

Des. 216,701

PAGE 2

FIG. 2

FIG. 3

FIG. 4

FIG. 5

FIG. 6

FIG. 7

FIG. 8

FIG. 1 is a front perspective view of a data processing console unit showing my new design;

FIG. 2 is a left side view thereof;

FIG. 3 is a front view thereof;

FIG. 4 is a front perspective view of the unit with the base omitted for clarity of illustration;

FIG. 5 is a left side view thereof;

FIG. 6 is a top plan view thereof;

FIG. 7 is a rear view thereof; and

FIG. 8 is a bottom plan view thereof.

The side of the console unit not shown is substantially the same as the side shown.

I claim:

The ornamental design for a data processing console unit, substantially as shown and described.
